Inventor:

Harvey J. Flegal
By A. Beverston
Attorney.

UNITED STATES PATENT OFFICE.

HARVEY J. FLEGAL, OF CLEARFIELD, PENNSYLVANIA.

HANGER FOR COATS AND PANTS.

SPECIFICATION forming part of Letters Patent No. 566,509, dated August 25, 1896.

Application filed November 21, 1895. Serial No. 569,689. (No model.)

To all whom it may concern:

Be it known that I, HARVEY J. FLEGAL, a citizen of the United States, residing at Clearfield, in the county of Clearfield and State of Pennsylvania, have invented certain new and useful Improvements in Hangers for Coats and Pants; and I do declare the following to be a full, clear, and exact description of the invention, such as will enable others skilled in the art to which it appertains to make and use the same.

My invention relates to improvements in hangers for coats and pants, and is intended for the use of clothiers and tailors to display their goods to the best advantage, and also to preserve the shape of the clothing.

The invention consists in the novel construction and combination of parts herein-after fully described and claimed.

20 In the accompanying drawings, Figure 1 is a perspective view of a hanger constructed in accordance with my invention. Fig. 2 is an elevation, looking from the rear or back side thereof.

25 In the said drawings, the reference numeral 1 designates a curved bar, preferably of wood, provided with an upwardly-extending arm 2 secured to the bar near the center thereof. This bar extends forwardly, forming

30 a horizontal portion 3, then upwardly, forming a vertical portion 4, then backwardly, forming a portion 5. It is then extended upwardly and its extremity bent into a hook 6. The ends of said bar are connected by a

35 curved rod 7. Also secured to said bar 1 is a clamp 8, consisting of a piece of spring-wire bent over at the center, forming a horizontal portion 9, then upwardly, forming inclined arms 10, then inwardly, forming arms 12,

40 which pass each other and are then curved upwardly, forming arms 13. These arms are coiled at 14 and the ends driven into the bar.

The numeral 15 designates the pants-holder, consisting of a spring-metal rod, one end of which is secured to the bar, while the other end engages with a slot 16 formed therein.

45 The manner of using the device is as fol-

lows: The bar is engaged with the inner side of the shoulders of the coat and the front of the latter brought around the ends of the bar 50 and the lapels engaged between the lower end of the clamp and the rod 7. By this means the coat is hung upon the hanger in a manner calculated to display it to the best advantage, and the hanger may be hung upon a suitable 55 rack or frame or other object. To hang a pair of pants, the free end of rod 15 is disengaged from the slot in the bar 1, and the pants, folded as usual, engaged therewith. The said free end of the rod is then again engaged with 60 the slot, when the pants will be securely held on the hanger.

I do not limit myself to the particular details of construction herein shown and described, as many modifications thereof may 65 be made without departing from the principle of the invention. For instance, the rod 15 is not necessarily a spring-rod and the clamp 8 may be made in a number of different ways. The rod 7 may also be dispensed 70 with if desired.

Having thus described my invention, what I claim, and desire to secure by Letters Patent, is—

1. The combination with the curved hanger, the supporting-hook, the depending clamp and the brace-rod, of the pants-supporting rod, secured at one end to the hanger and the other end adapted to engage with a notch in the opposite end of the hanger, substantially 75 as described.

2. In a combined coat and pants hanger, the combination with the curved bar, the curved rod connecting the ends thereof, the spring-clamp and the hook, of the rod having one end secured to said bar and the other end fitting in a slot in the bar, substantially 85 as described.

In testimony whereof I hereunto affix my signature in presence of two witnesses.

HARVEY J. FLEGAL.
